UNITED STATES PATENT OFFICE.

IRA W. JONES, OF LEBANON, MAINE.

RACK-CLEANING DEVICE.

1,392,647.

Specification of Letters Patent. Patented Oct. 4, 1921.

Application filed December 9, 1920. Serial No. 429,429.

To all whom it may concern:

Be it known that I, IRA W. JONES, a citizen of the United States, residing at Lebanon, in the county of York and State of Maine, have invented certain Improvements in a Rack-Cleaning Device, of which the following description, in connection with the accompanying drawings, is a specification, like reference characters on the drawings indicating like parts in the several figures.

This invention relates to devices and apparatus for cleaning the racks or gratings that are placed across the intake end of a mill race and in similar locations to catch debris which otherwise would be carried to the turbines or other water driven apparatus by the inrushing current of water.

It is necessary at frequent intervals to clean off the sticks, leaves and other debris that lodges on the gratings, and it has been customary heretofore to perform this cleaning operation with the aid of a long handled rake. In many installations this work can be performed satisfactorily in this manner, but on the larger dams where the gratings are deep it is very difficult to perform this cleaning operation by hand. This is especially true at certain seasons of the year, particularly in the autumn, when leaves carried by the current of water collect in great quantities on the gratings, these accumulations occasionally being sufficient to cause a serious reduction in the flow of water to the turbines and thus interfere very materially with the service supplied by the turbines. Moreover, the difficulty of keeping the gratings clear with the apparatus now commonly used has been increased by the tendency in newer and larger installations to increase the depth of the gratings.

With a view to overcoming this difficulty it has been proposed heretofore to perform this cleaning operation by some power driven apparatus and various forms of apparatus of this character have been devised. None of these forms, however, so far as I have been able to learn, have proved satisfactory, and it is the chief object of the present invention to devise a thoroughly practical mechanism for cleaning these gratings.

The manner in which it is proposed to accomplish this object will be readily understood from the following description when

read in connection with the accompanying drawings, and the novel features will be particularly pointed out in the appended claims.

Referring now to the drawings,

Figure 1 is a view partly in vertical cross section and partly in side elevation illustrating a rack cleaning mechanism constructed in accordance with the present invention;

Fig. 2 is a front elevation of the mechanism shown in Fig. 1;

Fig. 3 is a cross sectional plan view on the plane indicated by the line 3—3, Fig. 1;

Fig. 4 is a front elevation of the rake;

Fig. 5 is a vertical cross sectional view of the rake;

Fig. 6 is a side elevation, partly in cross section, illustrating a portion of the mechanism that automatically stops the dumping operation;

Figs. 7 and 8 are side and plan views, respectively, of an additional part of the mechanism that performs the dumping operation;

Fig. 9 is a vertical cross sectional view of a part of the mechanism that raises and lowers the rake;

Figs. 10 and 11 are plan and side views, respectively, of additional mechanism for operating the rake; and

Figs. 12 and 13 are plan and side views, respectively of one of the belt shifting units through which the control of the apparatus is effected.

Referring first to Figs. 1, 2 and 3, it will be seen that the apparatus shown comprises a car indicated in general at 2, this car being mounted on a track 3 which runs along the top of the dam 4. The rake 5, in the position shown in Figs. 1 and 2, rests on an apron or runway 6 which is carried by the car and extends down close to the upper end of the rack or grating 7 that covers the intake end of the mill race. The rake 5 is mounted to reciprocate up and down over the grating 7, being guided partly on the grating and partly on the apron 6, and during its upward or raking movement it gathers debris from the grating, carrying it upwardly over the apron 6 and dumping it into the upper end of a canal 8 which lies between the track 3 and the up-stream side of the dam. A current of water flows through this canal and carries away the debris thus delivered to it. The rake is ar-

ranged to have both raking and dumping movements and the car carries a motor and suitable controlling mechanism for producing both of these movements of the rake. A 5 controlling mechanism also is provided to enable the motor to drive the car when it is desired to transfer the rake from one part of the grating to another.

Proceeding now to the detailed description 10 of the various parts of the apparatus, the rake 5 consists of a series of teeth preferably made of bars of angular cross section, as clearly shown in Fig. 4, these bars being riveted to other angular members 10 15 and 11, respectively, Fig. 5. The ends of the teeth are cut off at an angle, as shown in Fig. 5, to form points which project between the bars of the grating, and the downwardly projecting flange of the angular member 10 20 limits the entrance of the points of the teeth between the bars, this flange riding on the surface of the grating. The rake 5 is pivotally supported on a shaft 12 by strips or 25 clips 13 which partially encircle the shaft and are riveted to certain of the teeth and to the downwardly projecting flange of the angular member 11. This construction is clearly 30 illustrated in Figs. 4 and 5. A pair of cables 14 are connected to the forward portion of the rake and another pair of cables 35 15 connected to the rearward edge of the rake coöperate with the cables 14 to control the angular position of the rake. The teeth at the opposite ends of the rake are extended, as shown in Fig. 5, considerably beyond the right-hand side of the shaft and the cables 15 are connected to these extended members.

The shaft 12 forms part of a frame which 40 includes an upper shaft 16, side pieces 17-17 preferably of channel cross section, and a plate 18 which connects the side members 17-17 and is reinforced at both its upper and lower edges by angle members 45 19-19. This plate forms a back for the rake and prevents the debris from sliding backwardly off the teeth. The frame forms the support for the rake 5 and is itself supported or mounted on two pairs of rolls or 50 trucks designated at 20 and 21, respectively, the rolls 20 rotating on the ends of the upper shaft 16 while the rolls 21 rotate on the lower shaft 12. These lower rolls are much larger in diameter than the upper rolls and 55 they are each provided with a peripheral rib 22 which enters between the ribs of the grating 7 and prevents the rake from slipping sidewise on the grating. The cables 14 run over grooved pulleys or sheaves 23 60 which are rotatably mounted on the shaft 16, while the other pair of cables 15 run over similar sheaves 24 rotating on stub shafts which are supported in channel bars 25-25 secured to the upper part of the frame.

65 It will now be evident that if the two

pairs of cables 14 and 15 are wound together on a drum or are wound at the same speed, the rake will be drawn upwardly over the surface of the grating and will be held in a given angular position with reference to the 70 grating during said movement.

For the purpose of winding the two pairs of cables 14 and 15 simultaneously, they are led over suitable pulleys or sheaves 26 and 27, Figs. 1 and 2, to drums 28-28, Fig. 3. 75 Each of the cables 15, however, is also led from one of the pulleys 27 over a pulley 29 which is mounted on a movable axis, and the cable is led from this pulley over another one of the pulleys 27 and thence to the drum 80 28. The drums 28-28 are keyed to a hollow shaft 30 to which also is fixed a worm wheel 31 which meshes with a worm fast on the shaft 32. This shaft carries two loose pulleys 33 and 34, respectively, and the fast pulley 35 positioned between the loose pulleys. Open and crossed belts driven from pulleys on the main driving shaft 36 normally run on the respective pulleys 33 and 34, and these belts are controlled by pivoted belt 85 shippers 37 and 38. The construction of this controlling mechanism is best illustrated in Figs. 12 and 13. Referring to these figures it will be seen that the belt shipper 37 has pivoted thereto a link 39 which carries a roll 90 running in a cam slot 40 formed in a plate 41 which is mounted to slide horizontally in the upper part of the bearing bracket 42. The other belt shipper 38 is similarly connected to a link 44 carrying a roll which 95 runs in another cam path 45 in the plate 41. A hand lever 46 is fulcrumed on the bracket 42 and is connected by a link 47 to one end of the sliding plate 41. Consequently, when the operator wishes to rotate the drums 100 105 28-28 it is merely necessary for him to throw the hand lever 46 in one direction or the other to transfer either the crossed or open belt, as he desires, on to the fast pulley 35, it being understood, of course, that if the 110 open belt is thrown on to the fast pulley it will rotate the drums in one direction, while if the crossed belt is transferred on to the fast pulley it will rotate the drums in the opposite direction. 115

For the purpose of holding the drums stationary when power is not applied to them, and also for the purpose of stopping the rotation of the drums quickly when either of the driving belts are shifted from a fast to a loose pulley, a brake mechanism is provided to operate on the fast pulley 35. This mechanism comprises a brake shoe 48, Fig. 13, having a stud 49 projecting upwardly therefrom, this stud being connected 120 through a loose joint to the lower end of a bolt 50 which is threaded through the brake lever 51. A spring 52 which is coiled about an upright rod 53 supported in a stationary 125 part of the frame bears on the lever 51 and 130

normally holds the brake shoe 48 firmly against the surface of the fast pulley 35. In other words, this spring normally applies the brake.

For the purpose of moving the brake lever 51 in opposition to the spring 52, it is fulcrumed on the rounding end of a stud 55 and is connected by a link 56 to one end of a lever 57 fulcrumed at 58 and carrying a roll 59 which runs on the edge of the plate 41. This plate 41 is provided with cam lugs or projections 60 and 61, Fig. 12, between which the roll 59 rests when the plate 41 is in its neutral position, as shown in Fig. 12. When, however, the lever 46 is moved in either direction to shift one of the belts to the fast pulley, this movement of the belt 41 carries one of the cam lugs 60 or 61 under the roll 59 thus lifting this roll. and this motion is transmitted through the connections with the brake shoe to raise the brake shoe off the surface of the pulley 35.

It will now be understood that the rake is normally stationary and that it is merely necessary for the operator to move the hand lever 46 in one direction or the other for the purpose of either raising or lowering the rake. In order to relieve the operator from the necessity of stopping the movement of the rake when it has been either raised or lowered to the desired point, an automatic stopping mechanism is provided. This mechanism comprises a shaft 63, Figs. 10 and 11, driven by a sprocket and chain connection 64 with the drum shaft 30. The sprocket wheel 65 is splined to the shaft 63 and is also threaded thereon, but is prevented from moving longitudinally of the shaft by a dog 66. This shaft is threaded for a substantial distance from one end and consequently when the sprocket wheel 65 is rotated it not only rotates the shaft 63 but also moves this shaft endwise through its bearings. Near the opposite end of this shaft two dogs 67 and 68, respectively, are adjustably secured by set screws, and they are mounted at opposite sides of a bar 69 which is mounted to slide at right angles to the shaft 63. This bar carries two lugs 70 and 71, respectively, positioned for engagement with the respective dogs 68 and 67 when either of these dogs have been transferred by the endwise movement of the shaft 63 into the proper position to engage one of the lugs. One of these dogs moves the shaft 69 toward the right, Fig. 10, while the other moves it toward the left, and this motion is transmitted through a bell crank lever 72 and a link 73 to the sliding plate 41, thus moving the belt 41 back into its neutral position and shifting the belt that is on the fast pulley on to one of the loose pulleys. In other words, when the operator has once shifted the lever 46 into the proper position to move the rake in the desired

direction, the machine will automatically stop the movement of the rake at a substantially predetermined point. This point may be varied by adjusting the dogs 67 and 68 on the shaft 63.

The cables 14 and 15 are so adjusted that they hold the rake at substantially right angles to the grating during the upward or raking stroke of the rake. During this movement they clean the debris out of the grating, this debris being carried on the rake upwardly over the apron 6. When the rake arrives at substantially the upper limit of its movement it is then moved into an inclined or tipped position for the purpose of dumping the debris into the canal 8. This movement is produced by pulling on the cables 15 so as to tip the rake in a counter-clockwise direction about the shaft 12. It is for this purpose that the cables 15 are run over the pulleys 29. These pulleys are supported on a shaft mounted in trunnions (one of which is shown at 75, Fig. 1) that project upwardly from an I beam 76. The opposite ends of this beam are connected to the upper ends of connecting rods 77 and 78, respectively, the lower ends of these rods being connected, respectively, to a crank 79 and a crank pin 80 (see Figs. 2 and 9). The crank 79 is keyed to one end of a shaft 81 that lies within the hollow drum shaft 30, while the crank pin 80 is secured in a worm wheel 82 that is keyed to the opposite end of this shaft. This worm wheel is driven by a worm fast on the shaft 83, Figs. 10 and 11, having a fast pulley 84 and a loose pulley 85 mounted thereon. The loose pulley is belted to the main driving shaft 36 and the belt is controlled by a shipper 86, Figs. 3 and 8, which is operated from a hand lever 87 in exactly the same way that the belt shipper 38 is operated from the lever 46. That is, the lever 87 operates a sliding plate 88 like the plate 41 except that it has only one cam slot therein, this plate having connections with the shipper 86 and with a brake which operates on the fast pulley 84 similar to the corresponding connections and brake mechanism above described in connection with the controlling mechanism and that previously described are simply those necessitated by the fact that this mechanism requires a fast and loose pulley, whereas the mechanism previously described included a fast pulley and two loose pulleys.

This mechanism is so timed with reference to the hoisting and lowering mechanism which operates the rake, that the pulleys 29 are held at the upper limit of their movement while the rake is being raised. At the end of this raking stroke, however, the operator moves the dumping lever 87 forward thus transferring the belt on to the fast pulley 84 and thereby causing the shaft 81

- to rotate. This motion carries the crank 79 from the position in which it is shown in Fig. 1 through an angle of 180° , the pin 80 being similarly rotated and thus moves the 5 pulleys 29 downwardly and thereby shortens (so to speak) the cables 15 with reference to the cables 14. This produces the dumping movement of the rake which is desired at this time.
- 10 Mechanism is provided which automatically stops this tipping movement of the rake at substantially a predetermined point. It is evident that a half rotation of the crank 79 and pin 80 produces the dumping 15 movement of the rake and that another half rotation would straighten the rake or restore it to its original position. The automatic mechanism just mentioned, therefore, is arranged to stop the tipping movement 20 of the rake either in its dumping or straightened position.
- This mechanism is best illustrated in Figs. 6, 7 and 8 and it comprises two rolls 90 and 91 mounted at diametrically opposite 25 points on the face of the worm wheel 82. An arm 92 mounted fast on a rock shaft 93, which is supported in suitable bearings, has an end portion shaped to be engaged by either of the rolls 90 or 91. The movement 30 imparted to the rock shaft 93 upon such an engagement is transmitted through another arm 94 also fast on this shaft to a link 95 which connects this arm with one arm of the bell crank lever 96 fulcrumed at 97 and 35 having another arm 98 which is pivoted to a vertical rod 99. A curved bracket 100, Fig. 7, is secured to the upper end of this rod and carries a pin 101 which is adapted to enter a hole 102 in the sliding plate 88 40 when this plate is pushed forward into position to throw the belt on to the fast pulley 84. A spring 103, Fig. 7, is connected to the lower end of the handle lever 87 so that it is tensioned when the lever is thrown 45 forward to start the dumping mechanism, and this spring has sufficient strength to return the hand lever to its initial position again. When, however, the hand lever has been moved forward, the pin 101 drops into 50 the hole 102 and retains the plate 88 in its operative or running position until the pin is raised through the chain of connections just described and which are set into operation by the contact of one of the rolls 90 or 91 55 with the arm 92. When this occurs the spring 103 immediately returns the plate 88 to the position shown in Fig. 8 thus shifting the belt on to the loose pulley 85 and applying the brake to the fast pulley 84.
- 60 Assuming now that the rake is at the lower limit of its movement, the operator moves the hoisting lever 46 into the proper direction to cause the power driven mechanism above described to raise the rake thus carrying the load of debris up to the upper

edge of the apron 6. This upward stroke or movement of the rake is automatically stopped by the mechanism above described, and the operator then moves the dumping lever 87 forward whereupon the power 70 driven mechanism above described tips the rake into its dumping position and automatically stops it in this position. The operator next moves the hoisting member 46 into the reverse position thereby causing the 75 hoisting mechanism to lower the rake and this movement of the rake is automatically stopped when it has reached substantially the lower limit of its movement. The operator next moves the dumping lever 87 80 forward again thus causing the straightening of the rake into position for the next raking movement, the tipping movement of the rake of course being stopped automatically, as above described, when it has reached 85 its straightened or raking position.

It may here be pointed out that the apron 6 is provided at its upper portion with raised guides or tracks 105, Fig. 1, for the wheels 21 and on to which the wheels roll when 90 the rake nears the upper limit of its movement. These raised portions lift the rake into such a position that when the rake is tipped into its dumping position and is lowered again there is no danger of the 95 teeth or the depending flange of the part 20 catching on the upper edge of the apron.

For the purpose of moving the car 2 along the track, the car axle 106, Fig. 1, has a sprocket wheel 107 secured thereto which is 100 connected by a sprocket chain with another sprocket wheel 108, Fig. 3, mounted fast on a shaft 109 which is supported in suitable bearings. This shaft is connected by a sprocket and chain drive 110 to another shaft 105 111 having a fast pulley 112 and two loose pulleys 113 and 114, respectively, mounted thereon. This shaft 111 is controlled and operated by a starting and stopping mechanism exactly like that which operates the 110 shaft 32, this mechanism being controlled by an operating lever or handle 115, and being driven through open and crossed belts from the main driving shaft 36. Inasmuch as this starting and stopping mechanism is 115 exactly like that shown in Figs. 12 and 13, any detailed description of it here is unnecessary. It will be understood that it is merely necessary for the operative to push the lever 115 forward in order to move the 120 car in one direction and backward to move it in the opposite direction. Normally the lever is in a neutral position and a brake acting on the fast pulley 112 holds the car stationary.

125 Power may be supplied to the car from any convenient source. In the construction shown an electric motor 117, Fig. 2, is belted to a pulley 118 on the main driving shaft 36 and drives this shaft. Current may be 130

supplied to the motor 117 either through a trolley connection, a storage battery, flexible cable, or in any other convenient manner.

5 The apron 6 preferably is connected to the car through a hinge 120, Fig. 1, or through some other flexible joint which will allow the apron to have a certain amount of movement relatively to the car to accommodate itself to variations in the incline of the up-stream face of the dam, or to variations in the distance between the track and the up-stream edge of the dam. It will be seen from an inspection of Fig. 2 that this 10 apron is provided with upstanding edges 121 at its opposite sides to prevent the rake from slipping sidewise off the apron and these edges are flared outwardly toward the lower part of the apron so that they will 15 guide the rake into a central position on the apron as the rake is drawn upwardly in case such a guiding action should be necessary due to the rake having slipped sidewise on the grating. As above stated, however, the peripheral ribs provided on the 20 wheels 21—21 usually prevent any sidewise movement of the rake relatively to the grating. The apron also is provided with small trucks or rolls 122—122 which support it 25 on the up-stream face of the dam.

The car 2 preferably is equipped with a hoisting mechanism for the stop planks 124 which usually are employed in a dam. For this purpose each plank section is provided 30 with a ring bolt 125, Fig. 1, to be engaged by a hook 126 on the lower end of a cable 127 which is wound on a drum 128, Fig. 3, fast on a shaft 129. This shaft is supported in suitable bearings mounted on a frame 35 work which is secured to one side of the car, and it is driven through a clutch 130 of any convenient type. The clutch shown comprises a driven member fast on the shaft 129 and a driving member on a shaft 131 40 mounted co-axially with the shaft 129, the driving member being splined to this shaft so that it can be moved into or out of engagement with its co-operating clutch member. The shaft 131 is driven through a 45 worm gearing 132 from a cross shaft 133 having fast and loose pulleys 134 and 135, respectively, Fig. 1, which are belted to the main driving shaft 36. The clutch is operated by a lever 137 which extends downwardly to a point within convenient reach 50 of the operator.

The operation of this apparatus has been described so completely in connection with the foregoing description of construction, 55 that any further statement of operation is believed to be unnecessary. It will readily be appreciated however, that the invention provides an automatic rake cleaning apparatus of very sturdy and substantial construction which can be manufactured eco-

nomically, can be conveniently controlled and operated, which is particularly suited to those installations in which great difficulty has been experienced in keeping the grating clear with the usual hand operated 70 apparatus, and which generally meets the practical requirements for power driven cleaning apparatus.

It will also be understood that while I have herein shown and described the best 75 embodiment of the invention of which I am at present aware, that this disclosure has been made by way of illustration rather than by way of limitation, and that the invention may be embodied in many forms 80 differing in details of construction from that shown without departing from the spirit or scope of this invention.

What is claimed as new is:

1. The combination with a dam having a 85 mill race therethrough and a grating across said race, of a car mounted for movement along said dam above said grating, a canal in the upper part of said dam, and a power operated rake mounted on said car and operative to rake debris out of said grating and 90 deliver it to said canal.

2. The combination with a dam having a 95 mill race therethrough and a grating across said race, of a car mounted for movement along said dam above said grating, an apron carried by said car and movable therewith along the up-stream face of the dam, connections between said apron and car permitting a relative movement between these 100 two members, and a rake mounted on said car and operative to clean the debris out of said grating and carry it upwardly over said apron.

3. The combination with a dam having a 105 mill race therethrough and a grating across said race, of a car mounted for movement along said dam above said grating, an apron carried by said car and movable therewith along the upstream face of the dam, said 110 apron having a hinged connection with said car whereby a relative movement is permitted between the apron and car, and a power operated rake mounted on said car for cleaning debris out of said grating and 115 carrying it upwardly over said apron.

4. The combination with a dam having a 120 mill race therethrough and a grating across said race, of a car mounted for movement along said dam above said grating, an apron carried by said car and movable therewith along the up-stream face of the dam, connections between said apron and car permitting a relative movement between these 125 two members, wheels supporting the lower part of said apron, and a power operated rake mounted to move up and down over said apron and operative to clean debris out of said grating and carry it upwardly over the apron.

5. The combination with a dam having a mill race therethrough and a grating across said race, of a car mounted for movement along said dam above said grating, an apron 5 carried by said car and movable therewith along the up-stream face of the dam, and a power operated rake mounted to move up and down over said apron and grating to clean the debris out of said grating and carry 10 it upwardly over the apron, the lower part of said apron being flared and having sides to guide said rake.
6. The combination with a dam having a mill race therethrough and a grating across 15 said race, of a track running along the top of the dam, a canal in said dam between said track and the up-stream side of the dam, a car mounted on said track, and a power operated rake mounted on said car and opera- 20 tive to rake debris out of said grating and deliver it to said canal.
7. The combination with a dam having a mill race therethrough and a grating across said race, of a motor car movable along said 25 dam above said grating, and a power operated rake mounted on said car.
8. The combination with a dam having a mill race therethrough and a grating across said race, of a car movable along said 30 dam above said grating, a motor mounted on said car for operating the car, a power operated rake mounted on said car for cleaning debris out of said grating, and means whereby said motor may be made to operate either the car 35 or the rake.
9. The combination with a dam having a mill race therethrough and a grating across said race, of a rake for cleaning the debris out of said grating, said rake having both 40 raking and dumping movements, and power driven mechanism for producing said movements.
10. The combination with a dam having a mill race therethrough and a grating across 45 said race, of a rake for cleaning the debris out of said grating, said rake having both raking and dumping movements, mechanism for giving said rake its raking movement, additional mechanism for producing said 50 dumping movement, and independent controlling means for said mechanisms.
11. The combination with a dam having a mill race therethrough and a grating across said race, of a rake for cleaning the debris 55 out of said grating, said rake having both raking and dumping movements, power driven mechanism for operating said rake, and means for automatically stopping the rake when it has completed a raking and 60 dumping movement.
12. The combination with a dam having a mill race therethrough and a grating across said race, a rake for cleaning debris out of said grating, power driven mechanism for 65 operating said rake, and means for auto- matically stopping the rake after it has completed a predetermined operation.
13. The combination with a dam having a mill race therethrough and a grating across 70 said race, a rake for clearing debris out of said grating, power driven mechanism for operating said rake, means for automatically stopping the rake at a substantially predetermined point in its cycle of movements.
14. The combination with a dam having 75 a mill race therethrough and a grating across said race, a rake mounted to reciprocate up and down over said grating to clean debris out of the grating, power driven mechanism for operating said rake, and means for 80 automatically stopping said rake at sub- stantially the upper limit of its movement.
15. The combination with a dam having a mill race therethrough and a grating across 85 said race, a rake mounted to reciprocate up and down over said grating to clean debris out of the grating, power driven mechanism for operating said rake, and means for automatically stopping said rake when it has completed its cycle of operations. 90
16. The combination with a dam having a mill race therethrough and a grating across said race, a rake mounted to reciprocate up and down over said grating to clean debris out of the grating, power driven mechanism 95 for operating said rake, and means for automatically stopping said rake at the lower limit of its movement.
17. The combination with a dam having a mill race therethrough and a grating across 100 said race, of a rake mounted to reciprocate over said grating to clean debris out of the grating, said rake comprising a series of teeth, and a frame supporting said teeth for tipping movement relatively to the direction 105 of said reciprocating motion.
18. The combination with a dam having a mill race therethrough and a grating across 110 said race, of a rake mounted to reciprocate over said grating to clean debris out of the grating, said rake comprising a series of teeth, and a frame supporting said teeth for angular movement relatively to said frame.
19. The combination with a dam having a mill race therethrough and a grating across 115 said race, of a rake mounted to reciprocate over said grating to clean debris out of the grating, said rake comprising a series of teeth, and a frame supporting said teeth for movement either into a raking position in 120 which the teeth project into the spaces be- 125 tween the bars of said grating, or into an angular position away from said grating, and means for moving said rake upwardly while it is in its raking position and down- wardly again over said grating while it is in said angular position.
20. The combination with a dam having a mill race therethrough and a grating across 130 said race, of a rake mounted to reciprocate

over said grating to clean debris out of the grating, and wheels supporting said rake on said grating, said wheels and grating having interengaging members serving to prevent 5 the rake from slipping sidewise on the grating.

21. The combination with a dam having a mill race therethrough and a grating across said race, of a rake mounted to reciprocate 10 over said grating to clean debris out of the grating, and wheels supporting said rake on said grating, the peripheral surfaces of said wheels being ribbed circumferentially to mesh with said grating and prevent the rake 15 from slipping sidewise on the grating.

22. The combination with a dam having a mill race therethrough and a grating across said race, of a rake mounted to reciprocate up and down along said grating to clean the 20 grating, mechanism for giving said rake its cleaning movement, and means whereby the teeth of the rake are caused to travel downwardly over the grating at a substantially greater distance from the face of the grating 25 than during the upward movement of the rake.

23. The combination with a dam having a mill race therethrough and a grating across said race, of a rake mounted to reciprocate 30 up and down along said grating to clean the grating, mechanism for giving said rake its cleaning movement, said rake having teeth to enter the spaces between the bars of the grating, and means for limiting the extent 35 of said entering movement.

24. The combination with a dam having a mill race therethrough and a grating across said race, of a rake mounted to reciprocate up and down along said grating to clean the 40 grating, mechanism for giving said rake its cleaning movement, said rake having teeth to enter the spaces between the bars of the grating, and a member located adjacent to the ends of said teeth to bear on the face of 45 the grating and limit the movement of said teeth into said spaces.

25. The combination of a dam having a mill race therethrough and a grating across said race, of a car mounted for movement 50 along said dam above said grating, a motor carried by said car, a rake mounted on said car and operative to clean debris out of said grating, power driven mechanism for giving said rake both raking and dumping movements, and controlling mechanisms whereby 55 said motor may be made to operate the car and to produce said raking and dumping movements.

26. The combination of a dam having a 60 mill race therethrough and a grating across said race, of a rake for cleaning debris out of said grating, said rake being mounted for tipping movement, cables supporting the rake at opposite sides of the axis about which 65 it tips, means for winding said cables in uni-

son to lift the rake, and means for producing a relative movement of said cables to tip the rake.

27. The combination of a dam having a mill race therethrough and a grating across 70 said race, of a rake for cleaning debris out of said grating, said rake being mounted for tipping movement, cables supporting the rake at opposite sides of the axis about which it tips, means for winding said cables 75 in unison to lift the rake, means for producing a relative movement of said cables to tip the rake, and means for automatically stopping said relative movement when a substantially predetermined tipping action has 80 been produced.

28. The combination of a dam having a mill race therethrough and a grating across 85 said race, of a rake mounted to reciprocate up and down over said grating, said rake being movable into either a normal raking position or a tipped dumping position, and operating mechanism for said rake for moving said rake upwardly over the grating in said normal position, for tipping the rake after it 90 has reached substantially the upper limit of its movement to dump it, lowering the rake in its tipped position, and then straightening it in readiness for the next raking movement.

29. The combination of a dam having a mill race therethrough and a grating across 95 said race, of a rake mounted to reciprocate up and down over said grating, cables supporting said rake, drums on which said 100 cables are wound to raise the rake and unwound to lower the rake, mechanism for driving said drums, and means for automatically stopping the drums substantially when the rake has reached either the upper or 105 lower limit of its movement.

30. The combination of a dam having a mill race therethrough and a grating across 110 said race, of a rake mounted to reciprocate up and down over said grating, cables supporting said rake, drums on which said 115 cables are wound to raise the rake and unwound to lower the rake, mechanism for driving said drums, and means operated by said mechanism for automatically stopping the drums when a substantially predetermined movement of the rake has been completed.

31. The combination of a dam having a mill race therethrough and a grating across 120 said race, of a rake comprising a series of teeth, a shaft extending transversely of the teeth and on which the teeth are pivoted, wheels mounted for rotation on said shaft, and means for moving said rake up and 125 down over said grating.

32. The combination of a dam having a mill race therethrough and a grating across 130 said race, a rake comprising a series of teeth, a frame supporting said teeth for tipping

movement, wheels supporting said frame, and means for reciprocating said frame up and down over said grating.

33. The combination of a dam having a mill race therethrough and a grating across said race, of a rake for cleaning debris out of said grating, said rake being mounted for tipping movement, two sets of cables supporting the rake at opposite sides of the axis 20 about which it tips, power driven drums for winding both sets of cables in unison to lift the rake, and means for acting on one set of cables between the drums and the rake to tip the rake.
- 10 34. The combination of a dam having a mill race therethrough and a grating across

said race, of a rake for cleaning debris out of said grating, said rake being mounted for tipping movement, two sets of cables supporting the rake at opposite sides of the axis 20 about which it tips, power driven drums for winding both sets of cables in unison to lift the rake, pulleys rotatable on stationary axes on which said cables are guided to said drum, additional pulleys mounted on movable axes on which one set of said cables is guided, and power operated mechanism for giving said additional pulleys a bodily movement to tip said rake.

25 In testimony whereof I have signed my 30 name to this specification.

IRA W. JONES.
